US00D788043S

(12) **United States Design Patent** (10) **Patent No.:** **US D788,043 S**
(45) **Date of Patent:** **** May 30, 2017**

(54) **ADJUSTABLE ELECTRICAL CONNECTOR**

(71) Applicant: **Bridgeport Fittings, Inc.**, Stratford, CT (US)

(72) Inventor: **Lawrence J. Smith**, Stamford, CT (US)

(73) Assignee: **BRIDGEPORT FITTINGS, INC.**, Stratford, CT (US)

(**) Term: **15 Years**

(21) Appl. No.: **29/533,611**

(22) Filed: **Jul. 20, 2015**

(51) LOC (10) Cl. **13-03**

(52) U.S. Cl.

USPC **D13/151**

(58) **Field of Classification Search**

USPC D13/133, 149, 150, 151, 153, 154, 156,

(57) **CLAIM**

The ornamental design for an adjustable electrical connector, as shown and described.

DESCRIPTION

FIG. 1 is a front perspective view of an adjustable electrical connector of my new design shown in environmental use.

FIG. 2 is a right side view thereof.

FIG. 3 is a left side view thereof.

FIG. 4 is a top view thereof.

FIG. 5 is a bottom view thereof.

FIG. 6 is a front view thereof.

FIG. 7 is a rear view thereof.

FIG. 8 is a side view thereof shown in environmental use.

FIG. 9 is a front perspective view of an alternative embodiment of the adjustable electrical connector shown in environmental use.

FIG. 10 is a right side view of the alternative embodiment.

FIG. 11 is a left side view thereof.

FIG. 12 is a top view thereof.

FIG. 13 is a bottom view thereof.

FIG. 14 is a front view thereof.

FIG. 15 is a rear view thereof; and,

FIG. 16 is a side view of the alternative embodiment shown in environmental use.

The broken lines shown represent unclaimed subject matter and form no part of the claimed design.

1 Claim, 12 Drawing Sheets
